(57) **CLAIM**

The ornamental design for a clamp for stick, as shown and described.

DESCRIPTION

FIG. 1 is front elevation view of a clamp for stick showing my new design;

FIG. 2 is right side elevation view thereof;

FIG. 3 is left side elevation view thereof;

FIG. 4 is rear elevation view thereof;

FIG. 5 is top plan view thereof;

FIG. 6 is bottom plan view thereof;

FIG. 7 is perspective view thereof; and,

FIG. 8 is perspective view.

The broken lines depict environmental subject matter only and form no part of the claimed design.
